UNITED STATES PATENT OFFICE

ANTHONY L. ASTE, OF BROOKLYN, NEW YORK, ASSIGNOR TO GRIFFIN MANUFACTURING COMPANY, INC., OF NEW YORK, N. Y., A CORPORATION OF NEW YORK

DAUBER

Application filed June 9, 1931. Serial No. 543,201.

An object of the invention is to provide a dauber which is inexpensive to manufacture and which may be readily taken apart to permit of the replacement of worn parts.

5 Another object of the invention is to provide a dauber with a fabric which encloses a member, the fabric being secured in a casing which may be held by the fingers when using the dauber.

10 Still another object of the invention is to provide a dauber with a casing in which is disposed a block, preferably a block of cork, another member, which may be of an absorbent member, being disposed against the block and being enclosed by a cloth which has portions held between the block and the casing.

15 Additional objects of the invention will appear in the following specification in which 20 the preferred form of the invention is described.

In the drawing similar reference characters refer to similar parts in all the views, of which

25 Figure 1 is a perspective view illustrating the dauber,

Figure 2 is an enlarged sectional view of the dauber, and

30 Figure 3 is a view of the cork block and the felt absorbent member with the cloth as they are disposed and before the cloth is wrapped around and secured to the cork block.

35 By referring to the drawing it will be seen that the dauber is provided with a casing 10 which has a bead 11 therearound, this bead serving to prevent the fingers, when holding the casing, from slipping to the open end of the casing where they may be soiled. Disposed in the casing there is a block, preferably a block of cork 12, and disposed against the 40 outer side of the block of cork 12 there is a member 13 which is preferably absorbent as well as resilient. This member 13 may be a felt. It will also be understood that the cork member 12 is resistant to the passage of moisture and that it has a strong resistance to deterioration and, also, that it is compressible and resilient. It will also be seen that the 45 inner end of the member 13 is disposed within the casing and the outer end of the member

13 extends beyond the casing, as shown in Figure 2.

Disposed against the outer end and the sides of the member 13 there is a cloth or fabric 14, the cloth or fabric 14 having portions 15 which extend between the sides of the cork block 12 and the sides of the casing 10 and portions 16 which extend at the inner end of the cork block 12 and which are preferably secured thereto. As illustrated in Figure 2 of 55 the drawing the portions 16 of the cloth or fabric 14 are disposed over each other and are secured in place by a tack 17 which extends into the cork block 12. However, it will be understood that these portions 16 of the cloth or fabric 14 may be secured to the cork block 12 in any desired manner.

60 As illustrated in Figure 3 of the drawing, the member 13 is disposed on the cloth or fabric 14 with the cork block 12 disposed on the member 13, then, when the sides of the cloth or fabric 14 are disposed upwardly against the sides of the member 13 and the cork block 12, the said sides extend over the 65 top of the cork block 12 to which they are secured. The cork block 12, with the cloth or fabric 14 secured thereto, is then disposed in the open end of the casing 10 and shown in Figure 2, the inner end of the member 13 being enclosed within the sides of the casing 70 75 80 10.

What is claimed is:

1. In a dauber, a casing, a block having substantially parallel faces and disposed in the casing, an absorbent member having its inner portion disposed against the outer face of the block and within the casing, the outer portion of the absorbent member extending beyond the casing, and a cloth disposed over the absorbent member and having portions disposed between the casing and the block. 85 90

2. In a dauber, a casing, a cork block disposed in the casing, a felt member disposed against the cork block and extending beyond the casing, and a cloth disposed over the felt member and having portions disposed between the casing and the cork block. 95

3. In a dauber, a casing having a head with side walls extending from the head, a block disposed wholly within the casing and 100

having inner and outer faces and sides, the block having its inner face disposed at the head and its sides disposed within the side walls, an absorbent member having its inner portion disposed against the outer face of the block and with its sides at its inner portion disposed within the side walls of the casing, the outer portion of the absorbent member extending beyond the side walls of the casing, and a cloth disposed over the absorbent member and having portions disposed between the casing and the block and being secured to the block.

4. In a dauber, a casing having a head with side walls extending from the head, a block disposed wholly within the casing and having substantially parallel inner and outer faces, the peripheries of which are connected by the sides of the block, the block having its inner face disposed at the head and its sides disposed within the side walls, an absorbent member having its inner portion disposed against the outer face of the block and with its sides at its inner portion disposed within the side walls of the casing, the outer portion of the absorbent member extending beyond the side walls of the casing, a cloth disposed over the absorbent member and having portions disposed between the casing and the block, and means for securing the cloth to the inner face of the block.

5. In a dauber, a casing having a head with side walls extending from the head, a cork block disposed within the casing and having substantially parallel inner and outer faces and sides connecting the peripheries of the inner and outer faces, the block having its inner face disposed at the head and its sides disposed within the side walls, a felt member having its inner portion disposed against the outer face of the block and with its sides at its inner portion disposed within the side walls of the casing, the outer portion of the felt member extending beyond the casing, and a cloth disposed over the felt member and having portions disposed between the casing and the block and being secured to the block.
